TENNIS BALL RECEPTACLE

Walter Marx, Whitestone, N. Y.

Application March 22, 1937, Serial No. 132,206

4 Claims. (Cl. 150—52)

My present invention relates to a receptacle for tennis balls and more particularly to a construction of the above class in combination and co-operative with a tennis racquet cover or container.

An object of the invention is to provide means for confining a number or group of tennis balls within a container at or near the throat of the racquet.

10 A further object is to provide means for securing the cover of the racquet and the balls by a single instrumentality.

A wall of the container is provided with a slot or opening slightly larger or longer than the diameter of any one of the balls, through which slot said balls may be inserted and withdrawn and which functions as a partial trap, so that each ball must be removed and inserted by hand, one at a time, thus preventing their escape under 20 normal conditions.

This slot or opening is preferably through the underside wall of said container and as thus located, it would be hidden from view and could be termed a secret entrance to the receptacle or 25 container.

The ball container or pocket is formed by one or more pieces of preferably moisture-proof material such as that of the racquet bag or other appropriate material, which may be stitched or 30 otherwise secured to the racquet bag over the throat of the racquet within and follows closely the shape of the throat portion of the racquet for minimizing a bulky appearance when the open end of the racquet bag is closed and secured.

35 A further feature which will be appreciated by a tennis player resides in the fact that the tennis balls confined as shown and described will not interfere with the application of a racquet clamp for eliminating warpage when the racquet is not in use, and further, the position of the container or pocket places the balls very close to the line of balance for convenience and comfort in carrying the racquet.

The position of the pocket further serves to 45 protect the racquet strings from stretching strains when the racquet, through inadvertence, be deposited, pocket-side-down upon a hard surface. This position of the racquet, were the pocket placed near the center of the racquet, would cause 50 damage to the stringing by pressure of the balls, through the weight of the racquet, especially if left in that position for a length of time.

In a modified form of my invention the pocket may be of any convenient shape but preferably 55 of geometric trapezoid form in plan view, with

closed top, closed downwardly convergent sides and an open bottom or mouth, through which the tennis balls may be passed upwardly one at a time and grouped prior to closing the mouth of the racquet bag which is secured around the racquet handle by a tie string or by other means.

The edge of the pocket may be in-turned and securely stitched or otherwise connected to the racquet bag, or said edge may be out-turned and stitched for producing a patch effect.

Pockets made and located according to my invention may, if desired, be attached to both sides of the racquet bag in one or more groups.

In the accompanying drawing, I have illustrated different practical embodiments of the invention, but the construction shown therein are to be understood as illustrative only, and not as defining the limits of the invention.

In the above mentioned drawing:

Fig. 1 is a face view, partly broken away, of a 20 tennis racquet bag with my invention secured thereon, and a tennis racquet and a clamp thereon indicated;

Fig. 2 is a cross sectional elevation taken on the broken line 2—2 of Fig. 1;

Fig. 3 is a fragmentary view showing the racquet bag secured at its normally open end by a tie string or the like;

Fig. 4 is a face view similar to Fig. 1, but showing a slightly modified form of construction;

Fig. 5 is a cross sectional elevation taken on the broken line 5—5 of Fig. 4;

Fig. 6 is a diagrammatic side elevation of a tennis racquet and its cover shown with pockets for tennis balls secured to opposite sides of the 35 racquet cover.

Referring now to the drawing in detail, 10 designates a standard tennis racquet having the usual throat portion 11, merging into a handle 12 and for the purpose of this description, I shall 40 use the descriptive terms "top", "bottom", "upper", "lower", etc., when pointing out the positions or locations of the parts as here illustrated in the several views.

The racquet bag or cover 13, is shown in Figs. 45 1 and 2, as placed on over the racquet with its lower open mouth 14 or edge falling considerably below the throat of the racquet to provide wing portions 15, for folding around the upper portion of the handle 12 to be secured by a tie 50 string, strap or the like here shown at 16, fastened on the racquet cover 13 at some convenient point as 16a to close the bag.

In carrying out my invention, a pocket 17, here shown as of general triangular form in face view, 55

is attached to one wall or thickness 13a of the bag material 13, by stitching 18 or the like through said wall and through an inturned flange or margin 19 of the sides or side-walls 20, of said pocket and entirely around and within the pocket. 5

The bottom of this pocket is the top wall 13a, of the tennis bag or cover 13, and is provided with a slot or opening 22, preferably extending longitudinally of the bag with its center on the 10 median line of the racquet head and its handle 12, as indicated by dotted lines in Fig. 1. This slot 22 is of a width and length to permit, by a slight margin of space, the passage of the tennis balls, one at a time into and out of the pocket.

15 17 and constitutes, in effect, a partial-trap, so as to eliminate the possibility of escape or dropping out of the balls when the racquet cover is removed and handled.

The side edges of the slot 22, are turned upward and backwardly to form ball retaining shoulders 22a, (Fig. 2) and the doubled edges thus formed are reinforced by stitching 22b.

25 The pocket 17 is so located that the tennis balls therein either wholly or partially rest on the throat portion of the racquet frame as shown in Fig. 1, so that there is no injurious contact with the racquet strings should said racquet be placed pocket side down, and further, the balls within the pocket 17, will not interfere with the 30 application of a clamp indicated at 23 to prevent warpage of the racquet frame.

A modified form of pocket 17a, is shown in Figs. 4 and 5 of the drawing, in which, said pocket may take the face contour of a geometric trapezoid with the tennis balls 21 snugly housed within its head or upper portion; the lower edge 24 being open to form a mouth or entrance 25 through which the tennis balls may be passed.

40 The side and top walls of this trapezoid form of pocket have their edges turned outward to form a flange or margin 26 for securing the pocket by stitching or other attaching means to the racquet cover or bag.

45 The aforesaid mouth of the trapezoid shaped pocket 17a is reinforced by a tie string 27 secured at its longitudinal center or along its edge by stitching 28 to the upper layer of this pocket as shown in Fig. 4, with the ends of the tie string free for securing the gathered wings 15 of the 50 racquet cover and the lower open end of the ball pocket around the throat of the racquet which facilitates both the closing of the racquet bag and ball pocket and the confinement of the tennis balls in proper grouped relation by a single fastening means.

The above described pocket construction is for the accommodation of three tennis balls, but it will be understood that pockets of various shapes for the reception of various groups of tennis balls may be employed as desired without departing from the spirit of my invention and further, the pocket of my invention should be close fitting so that a yielding binding action is exerted on all balls in a pocket to produce a smooth tailored appearance and said pockets may be applied to opposite sides of the racquet bag in the position stated or in other positions on the surfaces thereof. 5

What I claim is:

1. The combination with a tennis racquet bag 15 having an open lower end, of a number of tennis ball pockets attached to the outer sides of the bag and substantially opposite the throat portion of the racquet therein; each pocket having a slotted entrance through a wall connecting 20 with the interior of said bag and means for closing the bag when the racquet is not in use.

2. In combination with a tennis racquet cover with an open end and a racquet within said cover, of a pocket for tennis balls fastened to 25 said racquet cover along all edges of said pocket; a wall of said cover having a trapped entrance to said pocket; retarding shoulders extending parallel with the edges of said trapped entrance and fastening means for closing the open end of 30 said racquet cover.

3. In combination with a bag having a normally open end and a tennis racquet disposed therein with its handle projecting through said opening, of a pocket for tennis balls having a closed outer side and an extended continuous side wall and circumscribed means for attaching the side wall to the outer side surface of said bag in a position opposite the throat portion of said enclosed tennis racket, an entrance into 40 said pocket from inside of the bag and means for closing the open end of said bag around said handle. 35

4. A tennis ball carrier comprising in combination with a tennis racquet bag having an open mouth; a pocket cut and shaped to receive in snug confinement a determined number of tennis balls, said pocket having a closed top and a surrounding continuous wall, circumscribed stitching for securing said pocket to a side of said bag at a point removed from said mouth, a passage for said balls between the bag and said pocket and means for closing the said mouth around the usual projecting racquet handle. 45 50

WALTER MARX.
